(57) **CLAIM**

The ornamental design for a display screen with graphical user interface as shown and described.

DESCRIPTION

FIG. 1 is a first image for a display screen with graphical user interface showing our new design;

FIG. 2 is a second image thereof;

FIG. 3 is a third image thereof; and,

FIG. 4 is a fourth image thereof.

The outermost broken lines shown in FIGS. 1-4 illustrate a display screen and form no part of the claimed design.

The appearance of the transitional image sequentially transitions between the images shown in FIGS. 1-4. The process or period in which one image transitions to another image forms no part of the claimed design.
